DISPLAY RACK FOR NECKWEAR OR THE LIKE

Lyons I. Jossem, Rochester, N. Y.

Application March 26, 1956, Serial No. 40,761

Term of patent 14 years

(Cl. D80—10)

FIG. 1.

FIG. 2.

FIG. 3.

Fig. 1 is a front perspective view of a display rack, for neckwear or the like, showing my new design;

Fig. 2 is a plan view of the rack; and

Fig. 3 is a sectional view of the rack taken on the line 3—3 of Fig. 1 and looking in the direction of the arrows.

I claim:

The ornamental design for a display rack for neckwear or the like, as shown.
